DEVICE FOR OPENING JARS

Harry J. Lebherz, Frederick, Md., assignor to The
Everedy Company, Frederick, Md., a corpora-
tion of Maryland

Application September 1, 1933, Serial No. 687,852

6 Claims. (Cl. 81—3.1)

My invention relates broadly to kitchen utensils and, more particularly to an improved device for opening jars and opening caps from bottles and food containers.

5 One of the objects of my invention is to provide an improved construction of combination tool adapted for performing a multiplicity of different operations including the opening of screw cap fruit jars and other receptacles of various 10 diameters, the removal of crown caps from bottles and the removal of seal caps from food containers.

Another object of my invention is to provide a construction of cover and cap removing tool 15 adapted for universal usages and wherein the tool is pressed as a single piece from sheet metal.

Still another object of my invention is to provide a construction of universal tool having sets 20 of cap engaging jaws which are inclined angularly with respect to each other for gripping screw caps of various diameters and for effecting the removal thereof from food containers in combination with means for removing crown or sealed caps from other types of food containers.

25 A further object of my invention is to provide a simplified construction of stamped metal jar cap or cover removing tool having cap or cover gripping means disposed in various offset planes for effecting the removal of caps or covers from 30 different classes of receptacles.

A still further object of my invention is to provide a construction of stamped metal tool having 35 a central crown and seal jar cap removing device and sets of peripheral cap engaging jaws tapered toward each other for engaging and removing screw caps of different diameters.

Still another object of my invention is to provide a form of manually operated jar cover and receptacle cap removing manually operative device as set forth more fully in the specification hereinafter following by reference to the accompanying drawings, in which:

Figure 1 is a bottom plan view of the kitchen utensil constructed in accordance with my invention; Fig. 2 is a central vertical longitudinal section taken on line 2—2 of Fig. 1; Fig. 3 is a transverse vertical section taken on line 3—3 of Fig. 1; Fig. 4 is a transverse vertical section taken on line 4—4 of Fig. 1; Fig. 5 is a top plan view of the device showing the same in the act of removing the screw top cap of a Mason jar; Fig. 6 is a bottom plan view of the device showing the same in the position as used when removing an anchor cap from a preserve jar and the like; Fig. 7 is a 55 side elevation thereof; Fig. 8 is a bottom plan

view of the device showing the same in the position to remove a crown cap from a bottle; Fig. 9 is a side elevation thereof; Fig. 10 is a top plan view showing a modified construction of kitchen utensil embodying my invention; Fig. 11 is a central vertical longitudinal section taken on line 11—11 of Fig. 10; Fig. 12 is a transverse vertical section taken on line 12—12 of Fig. 10; Fig. 13 is a transverse vertical section taken on line 13—13 of Fig. 10; Fig. 14 is a transverse vertical sectional view taken on line 14—14 of Fig. 11; Fig. 15 is a perspective view of the device showing the same arranged in a position to remove the screw top cap of a Mason jar; Fig. 16 is a detailed sectional view taken on line 16—16 of Fig. 15; Fig. 17 is a perspective view of the device showing the same arranged to remove a crown cap from a bottle; Fig. 18 is a perspective view showing the device arranged to remove the anchor cap of a preserve jar; and Fig. 19 is a perspective view showing the device in the act of removing a threaded bottle cap.

My invention is directed to a simplified construction of tool for opening jars and removing caps from bottles and food containers wherein 25 the device is stamped from a single piece of sheet metal and provided with a securing handle for effecting manual operation of the tool. The tool of my invention is provided with two sets of coacting jaws disposed in different horizontal 30 planes spaced one from the other. The sets of jaws are inclined toward each other on opposite sides of a central axis through the operating handle of the tool. The stamping tapers from a maximum width at the remote extremity of the 35 tool to a minimum width adjacent the handle end of the tool. The outer peripheral edges of the tool are turned over and directed toward each other and on these edges, serrations or oppositely directed teeth are formed for gripping a screw 40 cap such as the cover of a Mason fruit jar. The fact that the serrated or toothed edges are inclined toward each other enables the covers of jars of varying sizes to be gripped and removed by a simple twisting operation of the manually 45 operative tool. The sheet metal blank from which the tool of my invention is formed is provided with slotted portions which are inclined toward each other. The outer peripheral edges of the slotted portions are each provided with 50 serrations or teeth directed toward each other for gripping therebetween the screw cap of food containers of different sizes within a smaller range of sizes than the sizes of covers to which the other set of jaws may be applied. A central portion of 55

the tool intermediate the aforesaid slotted portions is outstruck to provide a crown cap or sealed cover engaging tongue against which, pressure may be exerted by the angular movement of the handle of the device for prying a crown cap or sealed cover from a bottle or food receptacle. In a simplified form of my invention, I eliminate the central portion of the blank and instead of providing the two slotted portions therein, the entire center of the blank is removed. In this form of my invention, the lug which serves for the removal of crown caps is formed on the blank adjacent the handle portion thereof and intermediate the inner serrated jaws. The remote end of the blank is offset from the central portion of the blank to facilitate the operation of the tool in the removal of anchor caps from sealed food containers. The several different cap engaging and removing means are disposed in different horizontal planes spaced one from another.

Referring to the drawings in detail, reference character 1 designates a metallic blank or stamping which is pressed from a single piece of sheet metal for forming the bottle cap and jar cover removing tool of my invention. The blank 1 is provided with a central portion 2 which is pressed into a plane offset from the plane of the side portions 3 and 4 of the blank. The laterally extending end portion of the blank which connects the side portions 3 and 4 is offset from the plane of the side portions 3 and 4, as represented at 5. The central portion 2 connects with the laterally extending portion 6 and is tapered to a position adjacent the opposite end of the blank. The blank is provided with a pair of diagonal slots on opposite sides of the central axis of the tool which separate the side portions 3 and 4 of the blank from the central portion 2, as illustrated in Fig. 1. The blank 1 tapers from a maximum width at the end of the tool across which the lateral portion 5 extends to a minimum width at the end 6 of the blank to which the tongue 7 is integrally connected. The tongue 7 receives handle 8 thereon. The tongue 7 is wedged into the internal bore 8a in handle 8 and is provided with a ferrule 9 which abuts against the edge of the lateral portion 6 of the blank 1. The central portion 2 of the blank is strengthened by means of an outstruck rib 12 which divides and extends along opposite portions of the central portion 2, as represented at 14 and 15. In order to further strengthen the tool, the lateral portion 6 of the tool is provided with outstruck ribs 17 and 18 which are directed generally toward the side portions 3 and 4 of the blank. An intermediate extension of the strengthening rib is provided at 16 directed along the central portion 2 of the blank and terminating adjacent the upstruck bend 10 which raises central portion 2 into the plane of the laterally extending portion 5 above the plane of the side portions 3 and 4. The handle portion 7 of the blank is strengthened by means of the longitudinally extending rib 19 struck from the metal of the tongue 7, as shown. The several ribs serve to stiffen the tool both longitudinally and laterally thereby permitting the tool to be safely used as a lever in the removal of caps and covers from bottles and receptacles.

The side portions 3 and 4 of the blank are provided with oppositely directed jaws having serrations or teeth therein at 20 and 21. The teeth 20 and 21 are directed toward each other and serve to grip screw caps of different diameters for effecting the removal of such screw caps upon the application of a twisting torque against the

handle 8. The outer peripheries of the side portions 3 and 4 of the blank are turned over and are directed toward each other in a horizontal plane which is spaced from the horizontal plane which contains the side portions 3 and 4. The outer peripheries of the side portions 3 and 4 are provided with teeth or serrations 22 and 23 therein which are directed toward each other. The teeth or serrations 22 and 23 taper toward each other so that screw caps on jars of different diameters may be engaged and removed by a simple twist of the tool.

The central portion of the blank 1 is upstruck in a position adjacent the laterally extending portion 5 to provide a lug 25 which is bent upwardly from the material removed from aperture 24 in the blank for thereby providing an engaging lug adapted for prying crown caps or seal caps from bottles or jars. The lug 25 is disposed in a plane which is offset from the plane of the teeth 20 and 21 on the jaws formed by the side portions 3 and 4 and also offset from the plane of the serrations or teeth shown at 22 and 23 on the rolled over edges of the side portions 3 and 4 of the blank. The rib 12 in the central portion 2 extends longitudinally of the lug 25 for thereby strengthening the lug for use in prying operations.

As illustrated in Figure 5, the tool may be slipped over the screw cap of a jar to a position in which the teeth 22 and 23 engage the jar cap for permitting a screw operation thereon for effecting the removal of the cap.

In the case of anchor caps or friction seal caps which are used on many types of food containers, as designated for example at 26 in Figures 6 and 7, the tool of my invention has the laterally extending portion 5 resting upon the top of cap 26 while the lug 25 engages the lower peripheral edge of the skirt of the cap 26 allowing the tool to be used for purposes of prying the seal cap from the jar or food container.

The tool of my invention is particularly useful in removing crimp or crown caps from bottles. In Figs. 8 and 9, I have shown the manner in which the laterally extending portion 5 of the tool 45 is rested upon the top of a crown cap 27 secured on bottle 28 with the lug 25 hooked beneath the lower edge of the skirt of the crown cap 27 preparatory to movement of the tool as a lever for prying the cap from the bottle.

Figures 10-19 illustrate a modified form of the tool of my invention. In this construction of tool, the blank 1 has the central portion thereof wholly struck out and removed, as represented at 30. The lug which is employed for removing seal caps or crown caps is formed integrally with the blank 1 adjacent the lateral end portion 6 thereof, as represented at 31. The lug 31 is disposed in a plane which is offset from the plane of the serrated edges 20 and 21 and the serrated edges 22 and 23 on the rolled over peripheries of the side portions 3 and 4. In both forms of the tool of my invention, the three different cap removing means are disposed in different horizontal planes spaced one from another. I employ the same method of strengthening the side portions 3 and 4 and the tongue 7 as provided in the form of my invention illustrated in Figures 1-9, that is, ribs 17 and 18 and central rib 16 which extend longitudinally of the lug 31. The rib 16 is formed in the tongue 7 for strengthening the tongue which extends through the bore 8a in handle 8. The rows of teeth 20 and 21 and the rows of teeth 22 and 23, in the form of my invention illustrated in Fig. 10, are shown disposed on a slight curve 75

or arc. Such an arrangement has the advantage of enabling a multiplicity of adjacent teeth to be brought into engagement with the surface of the screw cap which is to be removed. More purchase of the tool with respect to the screw cap is thereby obtained allowing the torque force to be more effective for removing the screw cap. The teeth 22 and 23 which are formed on the rolled over peripheral edges of the side portions 3 and 10 4 are inclined downwardly, as represented more clearly in Figs. 12 and 13 to afford a better grip on the cap which is to be removed.

Figure 15 illustrates in perspective view the manner in which the tool of my invention is operated for gripping the screw cap 32 of a Mason fruit jar indicated at 33. The rows of teeth 22 and 23 grip the upper portion of the cap 32 and serve to apply a turning torque thereto as the handle 8 of the tool is twisted, as represented in Fig. 15. The manner in which the rows of teeth grip the cap 32 has been shown more clearly in Fig. 16.

The manner of employing the tool of Fig. 10 to remove crimp or crown caps is shown in Fig. 17 wherein the crown cap 27 on bottle 28 is shown as providing a bearing surface for the cap 27 while lug 31 grips the lower peripheral edge of the skirt of the crown cap 27 for ejecting the cap from the bottle.

In Figure 18, I have shown the manner in which the friction or seal cap 26 is removed from jar 34 and in which the laterally extending end portion 5 is gripped beneath the lower edge of the skirt of the cap 26 while the side portions 3 and 4 serve as bearing means with respect to the cap 26 for raising the cap 26 from the container 34.

Figure 19 shows the application of the tool of my invention to a screw cap of relatively small diameter. The screw cap 35 is removed from the receptacle 36 by inserting the tool with the rows of teeth 20 and 21 thereon on opposite sides of the screw cap 35 and moving the tool to a position in which the tool grips opposite sides of the screw cap whereupon the tool may be revolved to twist the cap from the screw threaded terminus of the receptacle 36.

I have found the tool of my invention highly practical for manufacture and production inexpensively on a quantity basis. The tool is formed from a single sheet of pressed or stamped metal which renders manufacture of the device very simple. The universal application of the device to jars and receptacles to various types and sizes and the ability of the tool to quickly remove crown or crimp caps makes the tool a very desirable and convenient utensil.

While I have described my invention in certain preferred embodiments, I desire that it be understood that modifications may be made and that no limitations upon my invention are intended other than are imposed by the scope of the appended claims.

What I claim as new and desire to secure by Letters Patent of the United States is as follows:

1. A cap removing tool comprising a member including a pair of side portions tapered toward each other and laterally extending end portions interconnecting opposite ends of said side portions, and teeth formed on the opposite peripheral edges of each of said side portions, the teeth on the outer peripheral edges of said side portions being directed toward each other and extending in a plane offset from the plane of the teeth formed on the inner peripheral edges of

said side portions, and one of said laterally extending end portions being offset in a plane removed from the planes of said side portions and the peripheral edges thereof.

2. A cap removing tool comprising a member having a pair of side portions tapered toward each other, laterally extending end portions interconnecting said side portions, a central portion interconnecting said laterally extending end portions, strengthening ribs disposed in said central portion and between said side portions in one of the interconnecting end portions of said member, and teeth formed on the opposite peripheral edges of each of said side portions comprising cap removing means for caps of various sizes.

3. A cap removing tool comprising a member having a pair of side portions tapered toward each other, laterally extending end portions interconnecting said side portions, a central portion interconnecting said laterally extending end portions, strengthening ribs disposed in said central portion and between said side portions in one of the interconnecting end portions of said member, the outer peripheral edge of each of said side portions being disposed in a plane offset from the plane of said side portions and extending in the same direction as the corresponding inner edge, and teeth formed on the opposite peripheral edges of said side portions.

4. A cap removing tool comprising a member having a pair of side portions tapered toward each other, strip members interconnecting opposite ends of said side portions, one of said strip members being disposed in a plane offset from the plane of said side portions, a central portion interconnecting said last mentioned strip member with the opposite interconnecting strip member, said side portions having their extreme outer edges directed toward each other in a plane offset from the plane of said side portions, and teeth formed on the inner and outer peripheral edges of said side portions and defining cap removing means for caps of varying sizes.

5. A cap removing tool comprising a member having a pair of side portions tapered toward each other, strip members interconnecting opposite ends of said side portions, one of said strip members being disposed in a plane offset from the plane of said side portions, a central portion interconnecting said last mentioned strip with the opposite interconnecting strip member, said side portions having their extreme outer edges directed toward each other in a plane offset from the plane of said side portions, teeth formed on the inner and outer peripheral edges of said side portions, and strengthening ribs outstruck from said central portion and from one of said strips interconnecting said side portions.

6. A cap removing tool comprising a member formed from a single sheet of material and having a central portion and a pair of side portions tapered toward each other, said side portions extending in a plane offset from but parallel to the plane of said central portion, and teeth formed on opposite edges of each of said side portions; the teeth on the outer edges of said side portions being disposed in a plane displaced further than said offset plane from the plane of said central member, and directed toward each other for engaging a screw cap of a diameter greater than the diameter of a cap engageable between the teeth on the inner edges of said side portions.
